UNITED STATES PATENT OFFICE.

BENSON JONES GRANT, OF GRAVETTE, ARKANSAS.

ATTACHMENT FOR CLAW-HAMMERS.

1,201,171.

Specification of Letters Patent. Patented Oct. 10, 1916.

Application filed October 17, 1913. Serial No. 795,772.

To all whom it may concern:

Be it known that I, BENSON J. GRANT, a citizen of the United States, residing at Gravette, in the county of Benton and State 5 of Arkansas, have invented a new and useful Attachment for Claw-Hammers, of which the following is a specification.

The present invention appertains generally to claw hammers, and relates more particularly to an attachment for such hammers.

It is the object of the present invention to provide an attachment for claw hammers, which shall facilitate both the attachment of 15 the handle to the hammer head and the nail pulling qualities of the head.

With the foregoing and other objects in view which will be apparent as the description proceeds, the present invention resides 20 in the combination and arrangement of parts and in the details of construction hereinafter described and claimed, it being understood that changes in the precise embodiment of the invention can be made within the scope 25 of what is claimed without departing from the spirit of the invention.

The invention has been illustrated in its preferred embodiment in the accompanying drawing, wherein:

30 Figure 1 is a fragmental elevation of a claw hammer embodying the present improvement, the section being taken on the line 1-1 of Fig. 2. Fig. 2 is an end view of the hammer, looking toward the head. 35 Fig. 3 is a section view taken on the line 3-3 of Fig. 2. Fig. 4 is a perspective view of the improved attachment.

The claw hammer, as illustrated, is of common construction, and embodies a handle or helve 1, and head 2, the head having 40 a central eye or opening 3 receiving the outer end of the helve 1, and having the striking face 4 and nail extracting claw 5 at its respective ends. The claw has a curved cam 45 face extending from the eye.

The present attachment embodies a shoe or block 6, which may be constructed of malleable metal, or which may be cast or drop forged. The shoe 6 has its inner face 50 7 curved to conform to the curvature of the back of the hammer head 2 so as to abut snugly against the back of the head 2 over the eye or opening 3. The other or outer face 8 of the shoe 6 is curved so as to pro-

vide a cam face, the heel portion 9 of the shoe being relatively thick and rounded abruptly, while the toe 10 of the shoe is relatively thin or sharpened. The heel 9 of the shoe extends toward or is nearest the striking face 4 of the hammer head, while the 60 relatively wide and sharp toe 10 extends toward, or to, and slightly overlaps the butt end of the claw 5, the cam face 8 merging into the butt end of the claw 5. Particular attention is directed to the fact that one end 65 of the shoe is relatively sharp and overlaps the butt end of the claw, and that the shoe is increased in thickness to the other end, to present a cam face forming an unbroken extension of the cam face of the claw. 70

The shoe 6 is provided with the inwardly or downwardly projecting wedge or tongue 11 projecting from its inner face 7 and approximately centrally thereof, the wedge 11 standing transversely of the shoe 6, although 75 the same may be positioned longitudinally of the shoe if desired. The wedge 11 is adapted to be driven into the outer end of the helve 1 so as to spread the helve to bind it securely within the eye 3 of the hammer 80 head, the shoe 6 being provided with the apertures 12 directly in rear and advance of the wedge 11, through which the wood screws 13 may be passed to take into the end of the helve 1. The apertures 12 and screws 85 13 are preferably counter sunk so that the heads of the screws may lie flush with the cam face 8 of the shoe. The shoe 6 is of a width from end to end equal to the width 90 of the head 2, in order that the sides of the shoe may lie flush with the sides of the hammer head, the corners of the shoe between the sides and cam face being preferably rounded, as seen in Fig. 3.

In applying the attachment to a claw 95 hammer, the wedge 11 is driven into the outer end of the helve, so that the inner face 7 of the shoe abuts snugly against the hammer head 2, it being understood that the present invention is applicable to various claw hammers now in use. The screws 100 13 are then inserted through the apertures 12 and screwed into the end of the helve 1 to clamp the shoe 6 in position. The wedge 11 in engaging within the end of the helve 105 will spread the same in order that the helve may be bound within the eye 3 of the hammer head, and the cam face 8 of the shoe

6 will coöperate with the curved claw 5 of the hammer head for facilitating the extraction of nails and the like. Thus, when the claw 5 is engaged in the head of a nail, 5 the nail may be partially pulled in the usual manner, and as the nail is being withdrawn, the hammer will ride upon the cam face 8 of the shoe 6, so that the nail may be conveniently extracted or pulled. The screws 10 13 in engaging the helve, and the shoe in overlapping the eye 3 or back of the hammer head 2, will assist in retaining the helve in position with respect to the hammer head, as will be apparent. The shoe 6 will 15 thus provide a neat and simple attachment for a claw hammer, the same not encumbering the hammer in any manner, but, on the other hand, providing a neat and sightly appearance as well as facilitating the attachment of the helve to the hammer head and the nail extracting qualities of the hammer head.

With the attachment applied to the head 25 of a claw hammer, the hammer will fill all of the requirements of the most efficient nail pulling hammers.

Having thus described the invention, what is claimed as new is:—

The combination with a claw hammer having the outer face of its claw curved 30 in the direction of its length, and a helve extending into the eye in the hammer head, of a shoe extending throughout the width of the head and having its outer face constituting practically a continuation of the 35 curve of the corresponding face of the claw, a single central transverse wedge integral with the shoe and entering that portion of the helve within the eye, and screws extending through the shoe directly in advance 40 and rear of the wedge and engaging the helve, the thickness of the shoe gradually increasing from the claw end thereof to the opposed end, said opposed end being abruptly rounded.

In testimony that I claim the foregoing as my own, I have hereto affixed my signature in the presence of two witnesses.

BENSON JONES GRANT.
